DESIGNER.

James Powell

085. 2258

James Powell, of Cincinnati, Ohio

Letters Patent No. 2,258 Dated January 30, 1864

Design for a Medallion of Gen. Grant.

The schedule referred to in these Letters Patent and making part of the same.

To all whom it may concern

Be it known that James Powell, of the City of Cincinnati, in the County of Hamilton and State of Ohio, have invented a new Design for a Medallion of Gen. General Ulysses S. Grant, and I do hereby declare that the same is clearly and correctly represented in the accompanying photograph, which is made a part of this specification.

I claim as new and desire to secure by Letters Patent

The design herein represented and described for a Medallion of Gen. General Ulysses S. Grant.

In testimony of which invention I have set my hand
Witnesses

Geo. W. Knight

James W. Payman
